CLAIM

The ornamental design for a table, as shown and described.

DESCRIPTION

FIG. 1 is a perspective view of a table;

FIG. 2 is a front elevation view thereof. A rear elevation view is a mirror image of the front elevation view;

FIG. 3 is a right side elevation view thereof;

FIG. 4 is a bottom plan view thereof;

FIG. 5 is a cross-sectional view taken along the line 5-5 in FIG. 2;

FIG. 6 is a cross-sectional view taken along the line 6-6 in FIG. 2;

FIG. 7 is a cross-sectional view taken along the line 7-7 in FIG. 3; and,

FIG. 8 is a perspective view thereof showing a table in an alternative position of use with one desktop lowered. The broken lines are used to show portions of the table that are not being claimed, and thus form no part of the claimed design.
